UNITED STATES PATENT OFFICE.

JAMES F. O'BRIEN, OF CHICAGO, ILLINOIS.

EXPLOSIVE.

1,073,279.

99 Drawing.

Specification of Letters Patent.

Patented Sept. 16, 1913.

Application filed November 13, 1912. Serial No. 731,088.

to all whom it may concern:

Be it known that I, JAMES F. O'BRIEN, a citizen of the United States, residing at Chicago, in the county of Cook, State of Illinois, have invented new and useful Improvements in Explosives, of which the following is a specification.

This invention relates to an explosive of the potassium chlorate class; and the prime and immediate object of the invention is the provision of a powder capable of various uses prepared by a simple single operation.

I will hereinafter set forth the advantages and various qualities of my improved explosive, first explaining its composition and method of manufacture, and the variations to which it may be subject.

I am aware that there has been used a simple combination of potassium chlorate and nitro-benzol, in the form of an explosive adapted to be prepared at the time and place of use; and that the explosives so formed are not adapted for storage or shipment mainly on account of their deliquescent qualities and on account of the evaporation of the nitro-benzol. I have developed and discovered a combination using a nitro-hydrocarbon, but a substance which gives distinctly superior results in that it at once water-proofs the explosive and binds in the chlorate from atmospheric deterioration, and is non-deteriorating in every way; at the same time making for plasticity necessary in cartridge form.

Fundamentally, my present explosive may be made up as follows: potassium chlorate 4 parts, binitrotoluene 1 part. There are other substances which I might substitute for the binitrotoluene and which will give quite similar results; but I prefer to use commercial liquid binitrotoluene.

I make a preferred form of explosive by adding to the above combination saw-dust or wood pulp or equivalent in the proportions approximately as follows: potassium chlorate 72 parts, binitrotoluene 18 parts, wood pulp or equivalent 10 to 25 parts.

An explosive of maximum strength is made by using approximately ten parts of the wood pulp or equivalent material; and this explosive I may use as a No. 1 explosive of greatest strength. For my No. 2 explosive I prefer to incorporate into the combination a certain proportion of a substance which I may generally designate as a restrainer. This restrainer may be one of

many different substances (sodium nitrate, common table salt, potassium nitrate, oxalate of ammonia, or other salts of oxalic acid, of oxalic acid and lime mixed together.) I 60 may prefer to use the sodium nitrate, and the preferred formula for my No. 2 explosive would then be as follows: potassium chlorate 55 parts, binitrotoluene 15 parts; sodium nitrate 15 parts, wood pulp or equivalent 20 parts. Not only is the sodium nitrate added but the proportion of chlorate and binitrotoluene cut down.

For my No. 3 explosive I prefer to use the following proportions: potassium chlorate 70 30 parts, binitrotoluene 15 parts, sodium nitrate 20 parts, saw dust, wood pulp or equivalent 25 parts.

I find that the above mentioned explosives are capable of use in a great many different 75 situations. Not only are they greatly useful for ordinary blasting where they are required to detonate when confined; but, they will also detonate when fired unconfined with a cap. Thus the explosive becomes 80 greatly useful for open blasting, stumping or the like. The direct object of using the substances classed as restrainers is the reduction of temperature of detonation, and at the same time, the increase of gas volume. 85 Reduction in temperature in detonation decreases the amount of flame and decreases the liability of ignition of surrounding material. Thus the explosives are adapted to use in coal mines and general mining work 90 where it is highly desirable that a "non-flame" explosive be used.

Using the wood pulp or saw-dust, or other equivalent (being more or less of the nature of disintegrated wood fiber), and in combination with the chlorate, I may use other, organic compounds, such as resin or the like, and with this resin combination I may or may not use restrainers such as I may use in the binitrotoluene combination. I make a 100 fundamental combination as follows: potassium chlorate 70 parts, resin 17.5 parts, wood-pulp, bran, saw-dust or equivalent 20 to 50 parts. And I may add stone coal (or other carbonaceous matter) as follows: 105 stone coal 10 parts.

When using the restrainer I may use any of those above noted, taking as typical the oxalic acid and lime. Potassium chlorate 60 parts, oxalic acid 25 parts, lime 5 parts, 110 resin 17.5 parts, bran, wood-pulp, saw-dust, or equivalent 10 parts. And a further varia-

tion I may substitute sugar or equivalent carbo-hydrate for the resin as follows: potassium chlorate 60 parts, sugar 20 parts, restrainer up to 30 parts. The sugar used in this combination is preferably dry and of the raw type known as "plantation." I have found that a mixture of this sugar with the chlorate and other ingredients (such as silicious material) will produce a plastic cartridge powder without the addition of moisture. A single simple mixing operation suffices to prepare this dry combination and delivers a plastic mass suitable for cartridge form. I may use the liquid binitrotoluene as a restrainer, and thus obtain a combination somewhat similar to that shown in my first formula, as follows: potassium chlorate 60 parts, sugar 20 parts, binitrotoluene, up to approximately 20 parts. With these sugar compounds I may use either silicious material or I may use a pulverized lime-stone or the like in varying proportions; for a No. 1 explosive I would use the mineral matter in about one half the amount of chlorate. For No. 2 I would use about three quarters the amount of chlorate; and for No. 3 about the same as the amount of chlorate. With the binitrotoluene combinations I may use a filler or carrier of an inert class, such as 30 pulverized lime-stone, to reduce the explosive violence where such is desired.

As to all of the above forms, and especially as regards the liquid binitrotoluene combination first given, with or without the various restrainers, I may set forth the following advantages: The explosive is made by a single simple mixing operation, the different ingredients being merely placed together in a suitable receptacle or simple machine and then thoroughly mixed. The resultant explosive is a smooth plastic mass which can be easily pressed into any required form and packed into cartridges for use as sticks. The mass is practically water-

proof and is non-deliquescent, the chlorate being bound in by the water-proofing of the liquid binitrotoluene. The explosive is non-deteriorating. It requires the action of a cap for its explosion: if ignited in open it will simply burn without explosive action; and concussion, jar or shock without heat will not cause it to explode. It is an explosive which may be classed as a "non-flame" explosive; and its detonation is absolutely sure and certain when it is acted upon by a strong cap. Whether unconfined or confined, when set off with a cap it will explode without fail; and this is a feature which is highly desirable in mining operations of all sorts. These and many other advantages are attained; but the salient points for which this explosive is noted are these—sure detonation of a non-flame plastic cartridge of non-deteriorating qualities, made in a simple manner from inexpensive materials. 65

Having described my invention, I claim:—

1. An explosive, comprising potassium chlorate, sodium nitrate, liquid binitrotoluene and finely divided woody matter. 70
2. An explosive, comprising potassium chlorate, sodium nitrate, liquid binitrotoluene and sawdust.
3. An explosive, consisting of potassium chlorate, sodium nitrate, liquid binitrotoluene and sawdust intimately mixed together. 75
4. An explosive, consisting of potassium chlorate and sodium nitrate together, about sixty parts, liquid binitrotoluene about fifteen parts, and sawdust about twenty-five 80 parts.

In witness that I claim the foregoing I have hereunto subscribed my name this 8th day of November 1912.

JAMES F. O'BRIEN.
